UNITED STATES PATENT OFFICE.

WALTER R. GROSS, OF ST. PAUL, MINNESOTA.

COIN HOLDER.

Application filed February 21, 1921. Serial No. 446,537.

To all whom it may concern:

Be it known that I, WALTER R. GROSS, a citizen of the United States, residing at St. Paul, in the county of Ramsey and State of Minnesota, have invented a new and useful 5 Coin Holder, of which the following is a specification.

My invention relates to coin holders and the object is to provide a device of said kind 10 with which a street car conductor or any other person using the device may readily extract from it the proper amount of coins he wishes to return to the street car patron or other person who has money coming on 15 any kind of transaction for which this device is applicable.

In the drawing:

Fig. 1 is a top view of the device with only 20 a portion of the coin cylinder cover shown.
Fig. 2 is a front elevation of Fig. 1 with the coin cylinder cover omitted.

Fig. 3 is a bottom view of the device.

Fig. 4 is a rear elevation of the main 25 frame.

Fig. 5 is an enlarged sectional elevation on line 5-5 in Fig. 1.

Fig. 6 is an enlarged inverted section on line 6-6 of Fig. 3.

Fig. 7 is an enlarged detail view of one of 30 the coin extractors.

Fig. 8 is an enlarged sectional view of 35 lower part of the device as on line 8-8 in Fig. 1.

Referring to the drawing by reference numerals, 9 designates a sheet metal main- 40 frame of L-shape in section, having end walls 10, and a double bottom consisting of an upper plate 11 and a lower plate 12. Near the front edge 13 of plate 11 I mount 45 a row of vertical tubes 14 of various diameters to receive various sizes of coins 15, said plate 11 having holes 16 to correspond to size of tubes and coins.

17 is a cover plate to fit over the tops of 45 tubes 14 and has slots 18 for insertion of coins; it is also provided with two or more screws 19 each with head 20 and their lower ends threaded to go into threaded holes 21 in bottom plate 12 (see Fig. 3) thus holding 50 the cover firmly.

Between the plates 11 and 12 and under each tube 14 I provide a coin extractor or slide 22 (see Fig. 7 for detail) of a thickness to correspond to thickness of coins used in

each tube, and having a hole 23 in its forward end, said hole being of a size also to correspond to the coin it is to move.

Back of holes 23 the slide is narrower forming shoulders 24 and in the narrow portion I punch a slot 25 the metal being bent 60 down at right angles and forming a tongue 26, and the rear end of the slide is bent upward at right angles to form an arm 27 for a purpose which will now be described.

The bottom plate 12 has slots 28 punched 65 out of it and part of the adjacent metal is bent inward and up forming flanges 29 which are spaced so that the narrow portion of slide 22 can be slidably inserted between them (see Fig. 6); the downwardly projecting tongue 26 of each slide projecting through a slot 30 in said plate 12 and the upwardly projecting arms 27 move in slots 31 in plate 11. The shoulders 24 of each slide 22 are normally held by a spring presently 70 to be described, in position against the ends of the flanges 29, which serve as stops for said shoulders and the coin openings 23 are then in position shown in full lines in Fig. 3. In said Fig. 3 I have shown semicircular 75 notches 32 in the bottom plate 12 slightly overlapping the opening 23 of each slide 22 when in normal position.

The upwardly projecting arms 27 of the slides are normally in position near the rear 80 wall of frame 9 and each of them is engaged by a vertical leaf spring 33 the upper end of which is clamped between the rear wall of frame 9 and a bar 34 threaded to receive a 85 screw 35.

In Fig. 8 I have shown a modified form of 90 coin slide 22 for extracting several coins at a time, the slide merely being provided with a collar 36 of predetermined height and the coin tube above it is modified in construction 95 as follows (see Figs. 1, 2 and 8): The tube 14 is simply made so its lower end terminates above plate 11 as at 14^a (in Fig. 8) and secured to the adjacent tube by spacers 37 (see Figs. 1 and 2) and a tight fitting slidable 100 inner tube 38 is inserted. This inner tube is raised or lowered according to height of collar 36 and held by a screw 39 in a boss 40 of outer tube 14 (see Fig. 8).

When the operator desires to hang this 105 device on his coat or other garment I have provided holes 41 with narrow upwardly extending slots 42 the object being to have

correspondingly spaced buttons on the coat to slip into said holes 41 and the device is then pushed down so the slots 42 will straddle the thread holding the buttons and 5 thus hold the device in place.

The slot 43 in plate 11 (Fig. 1) is provided to permit a slide 22 such as shown in Fig. 8 to slide outward.

In the use of the device the operator 10 simply puts coins of various sizes in their respective tubes or containers, the slides 22 and bottom 12 preventing coins from dropping through. When it is desired to extract coins the operator merely slips his 15 hand under the device, palm upward, to receive the coins, engaging one or more of tongues 26 with his fingers and pulling forward. When tongue 26 hits end of slot 30 the opening 23 of the slide and the coin 20 within it have reached position 23^x (Fig. 3) leaving the coin or coins free to drop into the palm of operator. The arm 27 has meantime reached position 27^x (Fig. 5) and spring 33 has been sprung accordingly, so that 25 when tongue 26 is released the spring goes back to normal position and retracts slide 22

to position to receive another coin from those stored in the tube.

Having thus described my invention what I claim is:

1. In a coin holder, an L-shaped frame, a plurality of coin tubes mounted on the horizontal part of the frame in spaced relation to the vertical part thereof, and a slidable coin ejector in said horizontal part for ejecting coins from each of said tubes, a vertically disposed leaf spring, for each ejector, removably secured with its upper end to the vertical wall of the frame and having its lower end in pressing contact with its corresponding coin ejector for the purpose described. 30

2. A coin holder having a vertical coin holding tube with a clearance space below it, and means for ejecting a coin or coins from 45 said space, said tube being composed of two telescoped members, and means for holding the inner member more or less projected into said space.

In testimony whereof I affix my signature.

WALTER R. GROSS.
